UNITED STATES PATENT OFFICE.

THOMAS BASON, OF ENGLEWOOD, ILLINOIS.

DOOR-LATCH.

SPECIFICATION forming part of Letters Patent No. 366,808, dated July 19, 1887.

Application filed January 15, 1887. Serial No. 224,435. (No model.)

To all whom it may concern:

Be it known that I, THOMAS BASON, of Englewood, in the county of Cook and State of Illinois, have invented a new and Improved 5 Door-Latch, of which the following is a full, clear, and exact description.

This invention relates to door-latches, the object of the invention being to provide an improved form of latch wherein the parts are 10 so constructed and arranged that the latch may be thrown into and out of engagement with the keeper by a simple pull upon the handle of the door.

To the end named the invention consists, essentially, of a pivotally-mounted handle provided with a lever-arm that is arranged to engage with a spring-pressed latch or locking-bolt, as will be hereinafter more fully described, and specifically pointed out in the 20 claims.

Reference is to be had to the accompanying drawings, forming a part of this specification, in which similar figures of reference indicate corresponding parts in all the views.

25 Figure 1 is a face view of a portion of the door provided with my improved form of latch. Fig. 2 is a side view of a portion of the door. Fig. 3 is a sectional elevation taken on line $x-x$ of Fig. 2. Fig. 4 is a view of the interior of 30 the latch, representing the same as it appears when arranged in connection with the door, the door being shown in section, and a portion of the latch-case cover being broken away in order to disclose the interior construction, the 35 operating-levers, which are arranged in connection with the latch and connected to the handle, being also shown in section. Fig. 5 is a sectional plan view taken on line $z-z$ of Fig. 1. Fig. 6 is a perspective view of one of 40 the lever-arms, which extend from the handle to the latching-bolt. Fig. 7 is a face view of the same lever-arm, and Fig. 8 is a central sectional view of the lower handle-supporting box.

45 In constructing such a latch as the one forming the subject-matter of this application, I provide a bolt, 10, that is formed with a central recess and an inclined-faced end, 11, which end is normally held extending beyond the 50 lock-piece by a spring, as will be hereinafter described. The rear walls of the central re-

cess, 12, of the bolt 10 are divided into sections, and these sections are inversely inclined, as shown at 2 and 3 in Fig. 5.

The bolt described is fitted within a case, 20, 55 which may be of the form illustrated in the drawings—that is, may be a combined lock and latch case—or the case might be a simple latch-case. The case 20 is provided with an upwardly-extending post, 14, while the bolt 60 10 is formed with an inwardly-extending post or projection, 15, about which there is coiled a spring, 16, that abuts against the post 14 and against the forward wall of the recess 12, as clearly shown in Fig. 4, the spring 16 acting 65 to hold the bolt 10 in the position in which it is shown in said Fig. 4—that is, acting to hold the bolt shot forward.

In connection with the latch described, I 70 employ a handle, 30, that is carried by two arms, 31 and 32, said arms being respectively provided with a projection, 7 and 7^a , which projections fit within apertures formed in boxes 33 and 34. One of the boxes (the box 33, as shown in the drawings) is made integral with the face-plate 34^a, while the other box is formed with an upwardly-extending lug or projection, 4, which passes through an 75 aperture, 5, that is formed in the plate, and bears against the inner end of said plate, the main body of the box being formed with a threaded socket to receive a screw, 6, which passes through the plate to engage with the box.

Upon the projection 7 of the upper arm of 80 the handle 30 there is fitted a lever-arm, 35, which arm is held against accidental displacement by a screw, 8, which passes up through the arm 31 and the projection 7 to engage with the lever 35, as best shown in Fig. 3. On the 85 projection 7^a of the arm 32 there is formed a downwardly-extending spur, 36, that fits within an apertured plate, 37, which said plate is in turn fixed to a spiral spring, 38, that is mounted within the box 34.

In order that the throw of the handles 30 may be limited, I prefer to form the arms 31 and 32 with toes 39, which are arranged to strike against the face-plate 34^a, and so limit the throw of the handles. An inspection of 90 the drawings will show that the handles may be secured to either side of the door, one han-

dle being arranged above the other, so that the lever-arms 35 of the two handles will overlap, passing at this time through properly-arranged apertures in the latch-case just in advance of the incline faces 2 and 3 of the rear wall of the bolt-recess 12.

From the construction described it will be seen that each handle may be operated independently of the other, and in closing the door 10 the latch-bolt will work independently of the handle. The only strain upon the latch-bolt spring is that necessary to keep the said bolt projected forward, and consequently the spring may be made light and flexible, so that it will 15 work easily. When the handles have been moved in the direction of the arrows shown in Fig. 5, so as to move their levers 35 in a direction to force the latch-bolt within the casting 20, the springs 38 will be put under tension, so that when the handles are released they will return the handles to their normal position. (Shown in Fig. 5.)

If deemed advisable, a plain band-spring—such as that shown in dotted lines in Fig. 4—25 may be used instead of the spring 16, and in case such flat spring is used I have found it desirable to groove the rear end of the bolt, so that the spring will fit within the recess so formed.

30 The latch described is simple, cheap, and durable, and not liable to get out of order, as there are only two movable parts in the latch-case, and as the direction of the pull required to throw the latch is the same as that required 35 to open the door the latch is almost automatic in its working.

The latch may be adjusted by varying the length of the lever 35 to any thickness of door, and as the handle on the outside of the right-hand door is the same as that on the inside of 40 a left-hand door, and vice versa, the latch can be used on either right or left hand doors without alteration or adjustment; and it will of course be understood that when it is desired 45 to open the door from one side only but one handle need be employed, and that if it is desired to reverse from right to left, or vice

versa, it can readily be done by taking off the removable boxes and changing the handles. The handles can be arranged to operate the 50 bolt from either the upper or the lower arm by attaching the lever to either, as desired, so that when the latch is used in connection with a lock the key-hole may be placed either above or below the handle.

55 The upright portion of the handle of such a latch as has been described may be made of any proper material, such as metal, glass, porcelain, wood, or rubber.

Having thus fully described my invention, I so claim as new and desire to secure by Letters Patent—

1. The combination, with a spring-actuating sliding bolt, of a pivoted handle, a lever connected to one pivot of the said handle and engaging the sliding bolt, and a spring on the other pivot of the handle for returning the same to its normal position, substantially as herein shown and described.

2. The combination, with a recessed bolt having its rear walls divided into two sections inversely inclined, and provided with a projection, 15, and the spring 16 on said projection, of the handle 30, provided with pivots 7 and 7^a, the pivots 7^a being provided with the extensions 36, the levers 35, connected to the pivot 7 of the handles, and the springs 38 on the extensions 36 of the pivots 7^a, substantially as herein shown and described.

3. The combination, with a sliding bolt 80 formed with a central recess, of a spring arranged within said recess, a handle carried by two arms that are mounted in boxes and connected to a face-plate, a lever-arm extending through the sliding bolt and connected to one 85 of the handle-arms, a spur, 36, connected to the other handle-arm, a plate, 37, with which the spur 36 engages, and a spring, 38, connected to the plate, substantially as described.

THOMAS BASON.
